UNITED STATES PATENT OFFICE.

LOUIS BENNETT HASBROUCK, OF ELMIRA, NEW YORK.

STARTER FOR INTERNAL-COMBUSTION ENGINES.

1,327,276.

Specification of Letters Patent.

Patented Jan. 6, 1920.

Application filed August 24, 1916. Serial No. 116,655.

To all whom it may concern:

Be it known that I, LOUIS BENNETT HASBROUCK, a citizen of the United States, and resident of Elmira, in the county of Chemung and State of New York, have invented certain new and useful Improvements in Starters for Internal-Combustion Engines, of which the following is a specification.

My invention relates to starters for internal combustion engines.

The principal object of my invention is to provide a starter for internal combustion engines that is solely automatic in operation.

15 The second object of the invention is to provide an automatic starter that may be used in conjunction with any type of gasoline engine.

20 Another object of the invention is to provide a starter of the above mentioned character which may be easily disassembled to apply a new part should one of the parts become broken.

25 An additional object is to provide a mechanical starter which is simple in construction, consists of few parts and is inexpensive to manufacture and which may be placed on the market at a comparatively low cost.

30 The above and other objects and advantages of my device will fully appear from the following description taken in connection with the accompanying drawings and be explicitly defined in the appended claims.

On the drawings,

35 Fig. 1 is a view of an internal combustion engine having my improved starter applied thereto.

Fig. 2 is a side elevation of my improved starter.

40 Fig. 3 is a view showing certain parts of the invention.

Fig. 4 is a vertical sectional view through the operating parts of the starter.

45 Fig. 5 is a front elevation showing the driving gear of the starter disengaged from the fly wheel of the internal combustion engine.

50 Fig. 6 is a like view showing the driving gear engaged with the fly wheel of the internal combustion engine.

Like characters of reference indicate like parts in all the views.

Referring to the drawings, the numeral 5 designates an internal combustion engine which may be of any type and the numeral 6 designates the fly wheel of the

same which is provided with gear teeth on its periphery. Supported on the engine casting or any other desirable place is an electric motor 7 having the armature shaft 8 extending therefrom. This motor 7 is operated by any suitable electrical system. Keyed to the shaft 8 is a sleeve 9 on which is keyed a gear 10. This gear 10 is cut away at one edge to provide an annular shoulder 11. Positioned on the gear 10 and abutting the shoulder 11 is a friction ring 12 having teeth 13 therein.

Loosely mounted on the inner end of the sleeve 9 is a bracket 14 which has formed integral therewith a bearing 15. Mounted in the bearing 15 is a stub shaft 16 having an enlarged end 17 which terminates in a head 18. Mounted on the enlarged end of the shaft 15 is a gear 19 having a recess 20 in its outer face which accommodates the head 18. This gear 19 is always in mesh with the gear 10 and is adapted to be thrown into and out of engagement with the fly wheel 6. A collar 21 is threaded upon the inner end of the sleeve 9 and bears against the bracket 14 and retains the same in position.

Pivottally mounted on the bracket 14 at the point of juncture with the bearing 15 is a locking pawl 22 which is substantially V-shaped and has an outwardly extending lug 23 formed at one end thereof. This locking pawl is normally engaged in one of the notches between the teeth 13 of the ring 12.

Secured to the motor 7 by means of screws or the like is a plate 24 on which there is an arm 25 having a cam surface 26 formed thereon, upon which the lug 23 rides. The arm 25 is provided with a recess 27 which accommodates an expansible spring 28. A pin 29 is also positioned in the recess 27 and is normally urged outwardly by the spring 28. The bracket 14 normally lies against this pin 29 and is supported in the position shown in Fig. 5.

Having described the different parts of the invention, the operation of the same will now be set forth: Assuming that the parts are in the position shown in Fig. 5, the motor 7 is now started which will rotate the gear 10 which in turn will rotate the gear 19 as indicated by the arrows. During the rotation of these gears, the engagement of the pawl 22 with the disk 12 will cause the bracket 14 to be swung to the position shown in Fig. 6 which will throw the gear 19 into

engagement with the teeth on the fly wheel 6. As this bracket 14 moves toward the fly wheel 6, the lug 23 moves upon the cam surface 26 which will throw the pawl 22 out of engagement with the teeth 13 of the friction ring 12. After the engine has started the gear 19 is thrown out of engagement with the fly wheel owing to the fact that the fly wheel is moving at a much greater rate of speed than the motor 7 which will throw the bracket 14 to its normal position and the pawl 23 will be rocked at the same time and engaged in one of the notches in the ring 12.

In order to prevent the bracket 14 from moving past the center of gravity on its outward movement, *i. e.*, when the gear 19 is being disengaged from the fly wheel 6, bracket 14 is formed with a lug 30 which abuts a lug 31 formed on the plate 24.

Having described the preferred embodiment of my invention, I desire it understood that the disclosure shown is illustrative only and that the invention can be modified and altered in many different respects that may fairly fall within the scope of the appended claims.

What I claim is:

1. A starter for internal combustion engines comprising, in combination with a rotating element of the engine, a shaft, a gear mounted on the shaft, a bracket loosely mounted on said shaft, a second gear carried by said bracket and meshing with the first-mentioned gear and adapted to mesh with said rotating element, and automatically operated means also mounted on the shaft whereby said bracket may be locked to said shaft to cause the bracket to be swung toward said rotating element to mesh said second-gear therewith to rotate the same.

2. A starter for internal combustion engines comprising, in combination with a toothed fly wheel, a shaft, a bracket loosely mounted on the shaft, a gear carried by the bracket adapted to mesh with the fly wheel, a second gear fixed to said shaft and meshing with the first mentioned gear, a toothed disk rotatable with the shaft, a pawl pivotally mounted upon said bracket and normally engaged with the disk, means for releasing the pawl from the disk when the first mentioned gear is brought into mesh with the fly wheel, and means for disengaging said gear from the fly wheel.

3. In a starter of the character described, a rotor, a bracket loosely mounted thereon, a driving element carried by the bracket and adapted to be operatively engaged with the fly wheel of an engine, a second driving element fixed to rotate with the rotor and operatively engaged with the first named driving element, means for normally retaining the bracket in an inoperative position and means rendering the first mentioned means inoperative to permit the bracket to move toward

the fly wheel to engage the first mentioned driving element therewith, upon the rotation of the rotor.

4. In an engine starter, a rotor, a bracket loosely mounted thereon, a driving element carried thereby and adapted to be operatively connected with the fly wheel of the engine, means operated by the rotor for rotating the driving element and swinging the bracket toward the fly wheel to cause the driving element to be operatively connected with the same, and resilient means co-operating with said bracket for normally retaining the bracket in a position where the driving element will be disconnected from the fly wheel.

5. In an engine starter, a rotor, a normally stationary member mounted thereon and capable of swinging movement, a gear fixed to rotate with the rotor adapted to rotate the fly wheel of the engine, and normally disengaged therefrom, a second gear carried by said member and meshing with the first named gear, a pivoted locking member for engagement with one of the gears to cause said member to swing toward the fly wheel and engage one of the gears therewith, the locking member being disengaged from the gear upon the completion of the movement of said member toward the fly wheel.

6. In an internal combustion engine starter, a rotor, a movable bracket mounted thereon and normally stationary, a driving element carried thereby, a second driving element operatively connected therewith and rotated by the rotor, and a pawl pivotally mounted upon the bracket and normally operatively connected with one of the driving elements to cause the bracket to move toward the fly wheel of the engine upon the rotation of the rotor to engage the other driving element with the fly wheel, the pawl being moved to inoperative position when the bracket has completed its movement toward the fly wheel.

7. In an internal combustion engine starter, a rotor, a movable bracket mounted thereon and normally stationary, a driving element carried thereby, a second driving element operatively connected therewith and rotated by the rotor, a pawl carried by the movable bracket, said pawl being adapted to normally lock said movable bracket with respect to the rotor, and a cam-way for rocking the pawl to render the same inoperative when the bracket has completed its movement toward the fly wheel.

8. In an internal combustion engine starter, a rotor, a bracket loosely mounted on the shaft of the same, a gear carried by the bracket, a second gear fixed to rotate with said shaft and meshing with the first named gear, a ring fixed to rotate with the second named gear, and a member normally

operatively connecting the bracket and ring to cause the former to move toward the fly wheel of the engine and engage the first named gear therewith, said member being 5 disengaged from the ring prior to the engagement of the first named gear with the fly wheel.

9. In an internal combustion engine 10 starter, a shaft, a bracket mounted on the shaft, a gear carried by the bracket, a second gear fixed to rotate with the shaft and meshing with the first named gear, a friction ring mounted on the shaft and having notches therein, a member normally engaged 15 in one of the notches in the ring to cause the bracket and ring to move as a unit toward the fly wheel of the engine and engage the first named gear therewith, and means 20 for disengaging the member from the ring prior to the engagement of the first named gear with the fly wheel.

10. In an internal combustion engine 25 starter, a shaft, a bracket mounted on the shaft, a gear carried thereby, a second gear fixed to rotate with the shaft and meshing with the first named gear, a ring frictionally 30 engaged with the shaft and adapted to rotate therewith and having notches therein, a pivoted pawl carried by the bracket and normally engaged in one of the notches in 35 the ring to cause the bracket to move toward the fly wheel of the engine and engage the first named gear therewith, and means for disengaging the pawl from the ring upon the completion of each movement of the bracket.

11. In an internal combustion engine

starter, a shaft, a bracket mounted on the shaft, a gear carried thereby, a second gear fixed to rotate with the shaft and meshing 40 with the first named gear, a ring frictionally engaged with the shaft and adapted to rotate therewith and having notches therein, a pivoted pawl carried by the bracket and normally engaged in one of the notches in 45 the ring to cause the bracket to move toward the fly wheel of the engine and engage the first named gear therewith, and a cam-way over which the pawl moves for disengaging the same from the ring upon 50 the completion of the movement of the bracket toward the fly wheel, said cam-way rocking the pawl into engagement with one of the notches in the ring upon the moving of the bracket away from the fly wheel. 55

12. In an internal combustion engine 60 starter, a shaft, a bracket mounted on the shaft, a gear carried thereby, a second gear fixed to rotate with the shaft and meshing with the first named gear, a ring frictionally 65 engaged with the shaft and adapted to rotate therewith and having notches therein, a pivoted pawl carried by the bracket and normally engaged in one of the notches in the ring to cause the bracket to move toward the fly wheel of the engine and engage the first named gear therewith, means for disengaging the pawl from the ring upon the completion of each movement of the bracket, and a spring urged lug normally supporting the bracket against movement in one direction. 70

LOUIS BENNETT HASBROUCK.
